United States Patent Office.

OSCAR C. FERRIS AND FREDERICK B. MILES, OF PHILADELPHIA, PENNSYLVANIA.

Letters Patent No. 104,948, dated July 5, 1870.

IMPROVEMENT IN STEAM-HAMMERS.

The Schedule referred to in these Letters Patent and making part of the same

To all whom it may concern:

Be it known that we, OSCAR C. FERRIS and FREDERICK B. MILES, of Philadelphia, in the county of Philadelphia and State of Pennsylvania, have invented a new and improved Steam-Hammer; and we do hereby declare that the following is a full, clear, and exact description thereof, which will enable others skilled in the art to make and use the same, reference being had to the accompanying drawing forming part of this specification.

This invention relates to certain improvements in the construction of the frame and valve-gear of steam-hammers which are used in the original manufacture, and in the subsequent forging of iron and steel. The object of the invention is to simplify the construction, and at the same time increase the efficiency of the steam-hammer, and to thereby facilitate the handling of the same in every respect.

In the accompanying drawing—

Figure 1 represents a front elevation, partly in section, of our improved steam-hammer.

Figure 2 is a horizontal section of the same.

Figure 3 is a detail side view of a modified construction of valve-gear.

Figure 4 is a detail top view of the same.

Figure 5 is a side view of another modified construction of the valve-gear.

Similar letters of reference indicate corresponding parts.

The steam-hammer herein referred to is of a class generally known as hammers with guides, although it possesses the advantages of the "no-guide" or open system.

Our invention consists, first, in setting the ram or drop A obliquely into the frame or guide B. Heretofore the rams are set flatwise or parallel with the faces of the frames, and guided by ribs and grooves. As for many purposes it is necessary to employ diagonal or "skew" dies, whose corners, however, must fall within the lower face of the ram, it is evident that but proportionately small dies can be used, whereas a large die or bit-surface is a very important desideratum in steam-hammers. By fitting the ram diagonally, or on a skew, into the frame, as is clearly shown in fig. 2, the above difficulties are entirely overcome.

The cross-section of the ram is oblong, as usual, and a plain oblong die, C, of the full size and shape of the end of the ram can, therefore, be keyed to it, and will pass up through the guides. This gives at once the required skew-die, besides affording the amplest extent of die-surface for any operation that can be performed under the hammer. The ram need only be made of the breadth and width of the largest die,

consequently it can be made much longer than usual, without exceeding the proper weight, and gives, therefore, a longer bearing on the guides. The latter may, therefore, be put much higher than usual, (see fig. 1,) leaving the working-space as unobstructed as in the no-guide system.

The anvil D is set at right angles to the ram, to support the lower die E parallel to the same, as shown. It will be seen that thus the greatest length of the die E is equal to the width of the anvil.

Our invention also consists in the arrangement of a new and simple valve-gear. The same is chiefly operated by a rock-lever or bell-crank, F, which is pivoted to the frame B, and which has one arm, a, connected by means of two, more or less, links, b b, with the crank-spindle G of the valve, and by one or more links, c, with a hand-lever, H, that is pivoted to the face or side of the frame.

The valve regulates, by its position, the admission and the amount of steam let into the cylinder I, in which the piston, which is, by a rod, J, connected with the ram, moves up and down.

The arm a of the bell-crank F rests lightly against the face of the ram, but it is not attached thereto.

On the face of the ram is formed, either at the bottom of a groove, e, as in fig. 1, or directly, as in figs. 3 and 5, an inclined face, f, which is in immediate contact with the arm a, and which, driving the reciprocating motion of the ram, causes the bell-crank to swing on its pivot.

The valve is perfectly balanced. Its weight, and that of the links b, resting upon the horizontal arm a, hold the vertical arm d against the inclined plane f of the ram.

If these should not suffice, an additional weight, g, may be employed, as indicated in figs. 3 and 4, or a spring can be used, if desired, or a rod, i, having a piston that works in a cylinder, l, as in fig. 5, may be employed to form an air-cushion to retard the motion of the valve, or an adjustable friction-clamp or stuffing-box may be used, which, by rubbing against some moving part of the valve-gear, will delay the descent of the valve.

By means of the lever H, the position of the valve can be regulated by hand when desired, and also the stroke of the bell-crank, which is adjusted in accordance with the requisite thickness of the forging. For the latter purpose the lever can be locked in any desired position by means of a pin, h, or its equivalent.

Thus, the lever can be used to instantly vary the length of each stroke. The die can, after a stroke, be retained upon the metal, and squeezed or pressed by

the force of the top steam. Again the ram can be raised to the very top of the stroke, held there as long as desired, then brought down gently or violently, as preferred, and, by a slight motion, set up again. Any desired number of blows can be struck all alike, or each can be varied at will. The apparatus is always in gear for self-acting, as well as hand-adjustment.

The following is the self-acting operation.

When the steam is turned on, the hammer rises and swings the bell-crank by means of its inclined plane *f*, the bell-crank shifting the valve. The position of the hand-lever determining at what point the steam is reversed from below to above the piston. The ram is now forced down by the top steam, while the valve has only its own weight, and that of the links *b*, &c., to lower it. But this weight is partly counterbalanced by that of the vertical arm *d*, and thus the descent of the valve is more or less delayed. The ram thus gets the start of the valve, and strikes the anvil before steam gets under the piston.

Figures 6 and 7 represent vertical sections of the steam-cylinder and valve-chest, and show their connection with the valve-operating mechanism.

A' represents the slide-valve operated by crank *G*. The throw of this crank is regulated by the toggle-arms *b b*. According as these arms approximate a coincidence in direction, or lie in the same straight line, is the upward throw increased, and vice versa.

Again, the relative position of these two arms is graduated by the lever *H* and link *C*. If the lever *H* is placed in position, as shown in fig. 6, the slide-valve will assume the position shown by dotted lines when the hammer rises to its highest point.

Fig. 6 shows hand-lever nearly at the bottom of its guide-bar, when, by lengthening the connecting-rod, the position of the valve is altered with relation to the piston, so that the valve is reversed much sooner during the up stroke, and the hammer returns again upon the anvil, after having risen only a short distance above it. The inclined plane *f*, although it forces the valve to reverse during the up stroke, has no effect upon it during the down stroke, and the valve descends by its own gravity, together with that of the links.

This descent is slightly retarded by the counterbalancing of the parts, so that the hammer reaches the iron on the anvil, driven by the top steam, with great violence, before the slowly-descending valve has had time to open the lower port to live steam, causing what is called a dead blow. If required, the descent of the valve may be further retarded by friction applied to the valve-rod or links, or other moving parts, or by a spring or air-cushion, or its equivalent.

Fig. 7 of the drawing shows the hand-lever nearly at the upper end of its guide-bar, which shortens the connecting-rod, drawing down the valve so as to confine the motion of the piston to the upper part of the cylinder, by causing the valve to reverse when the piston has descended a very short distance, as shown by the red lines. If the hand-lever is pushed to the extremity of the guide-bar, the valve will not open at all to top steam, and the hammer will remain suspended at the top of its stroke. If, on the contrary, it be pushed down to the very bottom of guide-bar, the valve cannot open to bottom steam, but will remain held down upon the anvil by the pressure of the top steam.

There are other methods of thus varying the position of the valve with relation to the piston. This one is known as Tannett and Walker's, while others, such as Morrison's, Davy's, William's, Seller's, &c., would do the same.

There are also other ways of making balanced valves. None of these matters, however, has anything to do with our invention, which confines itself, (so far as the valves are concerned,) exclusively to the manner in which the reciprocating motion of the hammer is conveyed to the valve, viz., by a rocker or bell-crank actuated by an inclined plane, unattached, so as to admit of delaying the descent of the valve. It will work as well with any other kind of balanced valve, or any other means of altering its position relative to the piston.

Having thus described our invention,

We claim as new and desire to secure by Letters Patent—

1. The arrangement of the hammer and anvil in relation to the hammer-frame, substantially as described, that is to say, so that the lateral faces of said hammer and anvil shall lie in planes oblique to the plane of the face of the hammer-frame.

2. A slide-valve, operated downwardly by gravity, combined with the incline *f* on the side of hammer *A*, and loosely pivoted lever *E*, having its curved end *d* in constant contact with the hammer-face, whereby the slide-valve is first raised to the height required, and then, in its fall, retarded, to prevent the steam-induction-inlet from being opened before the hammer has reached the point desired, all as shown and described.
